UNITED STATES PATENT OFFICE

2,225,767

MANUFACTURE OF METALLIC
RECEPTACLES

Harold W. Clark, Alliance, Ohio, assignor to The
Steel Sanitary Company, Alliance, Ohio, a cor-
poration of Ohio

Original application November 7, 1935, Serial No.
48,664, now Patent No. 2,176,738, dated October
17, 1939. Divided and this application March
8, 1939, Serial No. 260,575

1. Claim. (Cl. 113—120)

This invention relates to the manufacture of metal receptacles and, in particular, to receptacles made by the deep drawing of sheet steel. The invention will be disclosed as applied to the manufacture of bath tubs from sheet steel, but it will be apparent that other articles of like nature may be produced by the same method and apparatus, or with only slight modifications thereof. This application is a division of my copending application, Serial No. 48,664, filed November 7, 1935, now Patent No. 2,176,738, dated Oct. 17, 1939. Certain other subject matter disclosed in my said application Serial No. 48,664 and in this application but not claimed in either thereof is disclosed and claimed in my copending applications Serial Nos. 260,576 and 260,577, filed of even date herewith, which are also divisions of my said copending application Serial No. 48,664.

20 The manufacture of deep receptacles such as bath tubs, by welding sheet metal stampings or drawn blanks, presents numerous perplexing problems. It is found, for example, that after a blank has been drawn to form the drain end of the tub, it is impossible to further deform the bottom of the blank preparatory to providing a drain-hole, without fracturing the metal. This condition constituted a serious obstacle to the successful manufacture of sheet steel tubs because the fractured blanks could not be reclaimed but had necessarily to be scrapped.

I have invented a novel method of forming a drain-hole in the bottom of a receptacle made by a deep-drawing operation on a flat sheet, which overcomes the aforementioned objection to the procedure followed heretofore. In a preferred practice of the invention, I punch a hole in the bottom of the blank after the initial deep-drawing operation, at the point where the drain opening is to be located, and thereafter deform the metal adjacent the hole to provide the desired depending neck. I thus avoid the formation of cracks in the metal adjacent the drain-hole. The invention will be explained in detail herebelow by reference to the accompanying drawing illustrating one form of apparatus for forming blanks to constitute the drain end of a tub and the general appearance of the blanks for both the drain end and the other end of the tub, prior to their union by welding. In the drawing—

Fig. 1 is an elevation of blanks drawn from sheet steel in condition for welding together to form a tub; and

55 Fig. 2 is a central section through an appa-

ratus suitable for forming the blanks constituting the drain end of a tub.

I prefer to employ a so-called "toggle" press for forming the tub sections. As is well known, this is a form of mechanical press having two slides or vertically movable members adapted to operate in a predetermined succession. Since the construction of presses of this character is well known, it is not herein illustrated nor described. It is sufficient to state that the press has a work-supporting table in the form of a bolster adapted to support the dies through which the sheet is drawn, and at least two vertically movable slides adapted to operate in succession.

A bottom spacer 10, which is a box-shaped casting open at the top and bottom, is adapted to rest on the bolster. A draw ring 12 is secured to the bottom spacer 10. The draw ring is substantially U-shaped in outline, having an opening extending thereinto and rounded at the inner end, the edge of the opening being curved at the sides and rounded end thereof, as shown at 14. The upper surface of the draw ring 12 is provided with ribs, tongues or splines 15 extending along the sides and rounded end of the opening 13. The purpose of these splines will become apparent as the description of the apparatus proceeds.

A pressure pad 16 is reciprocable within the bottom spacer 10 by means of pneumatic cylinders having piston rods 18 slidable therein on which the pad rests. The supply of air to the cylinders is controlled by any suitable form of valve. The upper surface of the pad 16 is concave, to assist in shaping a metal sheet being drawn to the final contour desired in the finished product. The pad 16 is provided with a filler 44. The inner end of the punch, furthermore, is inclined as at 45. As a result, the inner end of the blank, as it is formed, is bent upwardly around the inclined end of the punch. This construction of the pad, filler and punch restrains flow of metal stock around the punch toward the closed end of the blank.

A blank holder ring 22 is mounted on one of the slides of the press, specifically that which descends first. The blank holder ring is simply a heavy plate or slab with an opening therein conforming generally to the outline of that in the draw ring 12. The blank holder ring is closed and the punch extension 26 is recessed at 41 to receive the inner cross member thereof. The undersurface of the blank holder ring has grooves 24 therein adapted to overlie the ribs or splines 15 on the draw ring 12. It will be apparent that

if a steel sheet is laid across the draw ring 12 while the blank holder ring 22 is elevated, the cooperating ribs or splines and grooves will serve to grip the edge of the plate, as indicated in Figure 2, and retard flow of the metal sheet therebetween as the central portion thereof is pressed inwardly and downwardly.

A punch 25 mounted on an extension 26 secured to the other slide of the press, viz., that which descends last. The punch 25 is shaped to produce the desired contour of the finished tub section.

The operation of the apparatus already described will probably be apparent but will nevertheless be reviewed briefly. The toggle press is first operated so as to withdraw the punch 25 and the blank holder ring 22. A steel sheet is laid across the draw ring 12. The press is then operated so as to cause the blank holder ring 22 to descend and grip the sheet 30 adjacent its edges. The pad 16 is then raised to meet the descending punch. The press is then operated so as to cause the punch 25 to descend and progressively shape the sheet from the flat condition, to the final form shown in Figure 2. As the punch descends and deforms the sheet, the edges and central portion thereof are stretched and deformed and there is actually some flow of the edges of the sheet between the draw ring and the blank holder ring. The cooperating splines and grooves on these parts, however, limit the inward flow of the sheet edges so that the deformation caused by the parts is largely taken up by the elongation of the central portion of the sheet. This makes it possible to employ as drawing stock a flat sheet having the minimum dimensions sufficient to form a tub so that the waste due to scrap is correspondingly reduced. At the same time the center portion of the blank is smoothly shaped to the desired contour. The pad 16 assists in giving the proper form to the finished tub section, being depressed against the air pressure in the cylinders 17 by the punch 25 as the latter descends.

The finished tub section has the appearance shown at 33 in Fig. 1, after the end of the section is trimmed off and the edges of the section sheared and flanged upwardly as shown at 32.

The method and apparatus above described, with some slight modification, may also be em-

ployed to form the other end of a tub such as indicated at 34 in Figure 1. In order to form a drain in the bottom of the drain end of the tub, I punch a hole centrally thereof. After punching a hole in the substantially flat bottom of the drain end, I then press the metal adjacent the hole out of the general plane of the bottom of the drain end, as shown at 46. I find that this method prevents fracture of the metal which occurred when it was attempted to deform the material surrounding the hole before punching the hole itself.

While it is quite possible to form tub sections in a single pressing operation as described above, I have found that the operation can be somewhat facilitated by making it in two stages and annealing the partly formed sections after the first operation at a temperature of between 1300 and 1400° F.

After the tub sections shown in Figure 1 have been produced, they are ready for joining, for example, by electric welding and, after the welded joint has been ground down, the finished tub can be annealed in the usual manner.

It will be apparent from the foregoing description that the invention provides a simple and effective method of providing a drain-hole in the bottom of a deep-drawn receptacle, without the formation of the cracks which have been encountered when following the procedure known heretofore. The method adds nothing to the cost of operations and effects a great saving in material which previously had to be scrapped.

Although I have illustrated and described but one preferred embodiment of the apparatus and practice of the method, apparatus and procedure other than that described may be employed without departing from the spirit of the invention or the scope of the appended claim.

I claim:

A method for making a blank for a deep receptacle having a bottom and a drain-hole therein, the steps including subjecting a flat metal sheet to a deep-drawing operation, thereby effecting a heavy cold-working by stretching of the portion of the sheet forming the bottom of the blank, forming a hole in the bottom of the drawn blank, and then, pressing the metal adjacent the hole out of the general plane of the bottom to provide a drain for the receptacle.

HAROLD W. CLARK.
